UNITED STATES PATENT OFFICE.

GODFREY STAIGER, OF TOLEDO, OHIO.

BUSHING-EXPANDER.

SPECIFICATION forming part of Letters Patent No. 736,647, dated August 18, 1903.

Application filed March 27, 1903. Serial No. 149,810. (No model.)

To all whom it may concern:

Be it known that I, GODFREY STAIGER, a citizen of the United States, residing at Toledo, in the county of Lucas and State of Ohio, have invented a certain new and useful Bushing-Expander; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

My invention relates especially to a machine for expanding the metal bushings commonly used in the bung-holes of barrels, kegs, or other closed vessels of the class required to be perfectly air-tight to prevent the leakage or fermentation of the contents thereof.

It is well known that in the filling of barrels, kegs, and the like with beer, vinegar, or other liquids great difficulty has been experienced in making the bung-holes of such vessels perfectly air-tight after the bungs have been inserted therein. In the endeavor to obviate this difficulty numerous styles of bushings—both single and double—have been devised, all of which are either worthless or are so expensive of manufacture as to depreciate their utility.

The object of my invention is to provide a machine that is cheap of construction and simple of operation whereby the single metal bushings commonly used in the bung-holes of barrels, kegs, &c., may be expanded after they have been driven or screwed therein, and thus make an absolutely air-tight vessel.

While the essential features of my invention are necessarily susceptible of modification, the preferred embodiment thereof is illustrated in the accompanying drawings, in which—

Figure 1 is a vertical longitudinal partly central sectional view of my invention, showing the position of the swaging-block when being inserted in a bung-hole. Fig. 2 is a vertical longitudinal central sectional view showing a portion of the handle and the position of the binding-nut and swaging-block during the swaging operation. Fig. 3 is a vertical central sectional view of a bushing

as it appears before it is expanded. Fig. 4 is a similar view of a bushing, showing the same expanded and a bung driven therein; and Fig. 5 is a vertical longitudinal view of a portion of the mandrel of my invention, showing the swaging-block thereof within the longitudinal slot provided for its reception.

Referring to the drawings, *a* represents the mandrel of my invention, which is preferably made circular in form and slightly smaller in diameter than the opening in the bushing *b*, which it is desired to expand. The upper portion of the mandrel *a* is squared, as shown at *a'*, to adapt it to receive and be turned by the wrench or handle *c*. The screw-threads *d* are provided on the mandrel *a* to receive the internally-screw-threaded binding-nut *e*, which has the annular flange or shoulder *e'* provided on its under side to seat within the upper flanged portion of the bushing *b*, as shown in Fig. 2, and thus hold the mandrel concentric with the bushing *b* and prevent the threads *d* from coming in contact with the inner periphery thereof.

A vertical longitudinal slot *f*, extending diametrically through the mandrel *a*, is provided near its lower portion to receive and house the swaging-block *g*, which is loosely supported on the pin *h* and adapted to swing in said slot *f*. The vertical edges of the swaging-block *g* when in its normal position, as shown in Fig. 2, are tapered so that the lower portion of said swaging-block extends a sufficient distance beyond the edges of the mandrel on each side to adapt it to have a wedge-like engagement with the lower inner edge of the bushing *b*, thus causing said edge to be forced outwardly when said swaging-block is held in close engagement with said bushing and the mandrel is turned. In order to provide means for tripping or turning the swaging-block *g* upon its supporting-pivot *h* to the position shown in Fig. 1, and thus enable the mandrel to be inserted or withdrawn from the bung-hole of the vessel, I form the horizontally-disposed longitudinal groove *i* on the upper edge of said swaging-block, near one end of which is pivoted the tripping or releasing rod *k*, which rod extends to a point above the upper end of the said mandrel through the obliquely-disposed vertical

bore or channel *l*. The swaging-block *g* is normally retained in the position shown in Fig. 2 by means of the expansion-spring *m*, which rests within the enlarged upper portion of the bore *l* and bears against the cap or thumb-piece *n*, secured to the top of the rod *k*. I do not confine myself to the use of the swaging-block *g* for expanding the bushing *b*, as I am aware that other means employing either a single or double swaging-block might be used equally as well, but I prefer the form shown as being the simplest and cheapest of construction.

While I have shown an ordinary handle *c* for turning the mandrel *a*, I preferably use a right-and-left ratchet-wrench, as I find that the turning of the mandrel *a* is thereby made easier.

In the operation of my machine the lower end of the mandrel *a* is inserted in the bung-hole of the vessel, the swaging-block being first tripped to the position shown in Fig. 1 to enable it to be passed to the interior of the vessel, where it is released and returns to its normal position, as shown in Fig. 2. The nut *e* is then turned down tightly by hand against the annular-flanged portion or rim of the bushing *b* and the mandrel given several turns within the nut *e*, which remains stationary in its seat, thereby causing the swaging-block to gradually rise as it turns with the mandrel. The lower inner edge of the bushing is thus expanded as the swaging-block is turned therein, and any leakage around the same is prevented.

It will be apparent by reference to Fig. 4 that after a bung *o* has been driven into a bushing expanded by my machine the liquid within the vessel will cause said bung to swell and tightly engage the expanded portion of the bushing, and thus prevent its being blown out.

Having thus described my invention, what I claim as new, and desire to secure by Letters Patent, is—

1. A bushing-expander comprising a turnable mandrel adapted to be inserted in a bushing, an elongated slot extended through and provided longitudinally of said mandrel, a swaging-block pivotally secured within said slot, spring-pressed means engaging with and adapted to trip said block, and means for causing said block to be drawn into engagement with and expand said bushing when said mandrel is turned, substantially as described.

2. A bushing-expander comprising a mandrel, a block having projecting tapered swaging edges pivotally secured to said mandrel, a rod extending above said mandrel and connected to said block and adapted when moved to cause said block to turn on its pivot and its projecting edges to be drawn within said mandrel, a bearing member threaded to said mandrel, and means for turning said mandrel.

3. The combination with a bushing, of a man-

drel having an elongated slot extending therethrough, a swaging-block pivoted within said slot, a rod connected to and adapted to turn said block, a member longitudinally movable on said mandrel and adapted to bear against the upper side of said bushing, and means for forcing said swaging means toward said member and expanding said bushing.

4. A bushing-expander comprising a mandrel having an elongated slot therein, V-shaped swaging means pivoted within said slot and adapted to be entirely inclosed within or to have its swaging edges projected beyond the same, a member longitudinally movable on said mandrel, and means for causing said swaging means and member to approach or recede from each other.

5. A bushing-expander comprising a mandrel having an elongated slot therein, a tapered swaging-block pivoted within said slot and having its tapered edges projecting beyond the edges of said mandrel, means provided for drawing the projecting edges of said block within said slot, an adjustable bearing member on said mandrel, and means for causing said block to approach said bearing member for the purpose specified.

6. A bushing-expander comprising a member adapted to be inserted in a bushing and having an elongated slot therein, a swaging-block pivotally secured within said slot, a nut threaded on said member and provided with an annular flange to adapt it to seat within the rim of said bushing and hold said member concentric therewith, and means for causing said swaging-block to be forced into and expand the bushing in which said member is inserted.

7. The combination with a bushing, of a mandrel adapted to be loosely inserted therein, a tapered swaging-block carried thereby, means for causing the tapered edges of said block to be inclosed within or project beyond said mandrel, a bearing member adjustably mounted on said mandrel, and means for causing said block to rotate within said bushing and approach said bearing means.

8. A bushing-expander comprising an elongated member adapted to be loosely inserted in a bushing and having a slot extending through a portion thereof, swaging means secured with said slot, a vertical bore communicating with said slot and extending to the upper portion of said member, a spring-pressed rod in said bore having connection with said swaging means and adapted to trip the same, a bearing element adjustably mounted above said swaging means, and means for causing said swaging means to be turned and approach said bearing member.

9. A bushing-expander comprising a mandrel having an elongated slot therein, a block having projecting swaging edges pivotally mounted within said slot, a spring-pressed member connected with and adapted to control the movement of said block, a bearing

element threaded to said mandrel and carrying an annular flange on its bearing-surface adapted to seat within the rim of the bushing operated upon and hold the mandrel concentric therewith, and means for causing said block to turn and approach said bearing element, substantially as described.

In testimony whereof I have hereunto signed my name to this specification in the presence of two subscribing witnesses.

GODFREY STAIGER.
